DRINKING CUP WITH HANDLE

Herbert Charles Behrens, Easton, Pa., assignor to American Can Company, New York, N.Y., a corporation of New Jersey

Filed Dec. 27, 1960, Ser. No. 63,348

Term of patent 14 years

(Cl. D44—9)

Fig. 2

Fig. 1

Fig. 3

The essential features of my design are shown in full lines.

I claim:

The ornamental design for a drinking cup with handle, substantially as shown and described.
